INVENTOR.

Harold E. Slork,

BY J. S. G.
Geo. F. Kimmel.
ATTORNEY.

UNITED STATES PATENT OFFICE.

HAROLD E. STORK, OF SAN ANTONIO, TEXAS.

ELECTRICAL SWITCHING MECHANISM.

Application filed April 9, 1927. Serial No. 182,366.

This invention relates to an electrical switching mechanism for controlling the circuits of electrically operated direction signals carried by motor driven vehicles, and has for its object to provide, in a manner as hereinafter set forth a mechanism of such class capable of being conveniently operated by the driver of the vehicle to selectively close the circuits of an electrically operated direction signal to indicate right or left turn or a change in direction of travel.

Further objects of the invention are to provide, in a manner as hereinafter set forth an electrical switching mechanism for the purpose referred to which is simple in its construction and arrangement, strong, durable, compact, thoroughly efficient in its use, capable of being installed in the vehicle within convenient reach of the driver thereof, and inexpensive to manufacture.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view of a motor driven vehicle, showing the adaptation therewith of an electrically operated direction signal of the type capable of being seen in signalling position from the front or rear of the vehicle and further illustrating in connection with the signal, an electrical switching mechanism, in accordance with this invention for controlling the circuits of the signal.

Figure 2 is an elevation, broken away and in longitudinal section of an electrical switching mechanism in accordance with this invention.

Figure 3 is a horizontal sectional view of the mechanism.

Figure 4 is a sectional plan of the mechanism and with the operating lever thereof broken away.

Figure 5 is an elevation of the signal.

Figure 6 is a longitudinal sectional view of the signal.

Figure 7 is a perspective view of the conductor member.

Referring to the drawings in detail 1 indicates the body of a motor driven vehicle, 2 the steering column, 3 the steering wheel, 4 a signal which is suspended laterally from one side of the body of the vehicle by a bracket or support 5, 6 a source of electrical energy, 8 an electrical switching mechanism in accordance with this invention and which is clamped to the steering column 2, and 7, 9, 10 and 11 circuit connections between the source 6, signal 4 and switching mechanism 8. The signalling system is of that type to permit of the signal 4 to be viewed from the front and rear of the vehicle or in other words whereby the signal can be indicated to a driver approaching from the front and a driver approaching from the rear with respect to that vehicle carrying the signal 4.

The signal 4 forms the subject matter of my application Serial No. 182,365, filed April 9, 1927, and will only be briefly referred to herein and it includes a casing 12 provided at its front and at its rear with a pair of signal plates 13, 14, one having an indication thereon, such as "Right" and the other having an indication thereon such as "Left". The signal plates at the rear of the casing, correspond to the signal plates at the front thereof. The signal plates 13 are green and the signal plates 14 are red. The casing is divided by a partition 15, forming a pair of lamp chambers 16, 17 and in each of which extends a lamp 18 which are in a normally open circuit. The bracket 5 is secured to the bottom of the casing 12, and is fixedly secured, as at 18, to the body portion 1 of the vehicle whereby the casing 12 will be disposed laterally with respect to said body portion as shown in Figure 1, so the signal will be perceptible from both the front and rear of the vehicle.

The switching mechanism, in accordance with this invention, comprises a plate of insulation, indicated at 19, to which is attached a cover member 20 of substantial height and which extends above said plate 19. The cover member 20 corresponds in contour to the contour of the plate 19 and as shown the latter is rectangular. The sides of the cover member 20, at the lower portions thereof, are slotted and the material freed by the slits is inturned to form inwardly extending flanges. The flanges are 110

indicated at 21, 22 and each is formed with a boss 23. Each flange is provided with an opening 24 extending through the boss and body of the flange and the wall of the opening is threaded. The flanges 21, 22 are arranged in spaced relation and seated upon the upper face of the plate 19. The cover member, other than the flanges 21, 22 abut against the edges of the plate 19, and said member 20 is connected to the plate 19 by holdfast devices 25 which extend upwardly through the plate 19 and have threaded engagement with the walls of the openings 24.

The plate 19 between the flanges 21, 22 and the outer end of said plate has extending upwardly therethrough a pair of binding posts 26, 27. The binding posts extend a substantial distance above the upper face of the plate 19 and each is provided with a plurality of superposed washers 28. The post 26 at its upper end is formed with a head 29, and the post 27 with a head 30. Interposed between the head 29 and the washers 28 mounted on the post 26 is a contact terminal 31, and interposed between the head 30 of the post 27 and the washers 28 mounted on such post, is a contact terminal 32. The contact terminals 31, 32 are oppositely disposed with respect to each other, as well as arranged in spaced relation, and each consists of a length of resilient, conducting material, bent upon itself and shaped in a manner whereby the ends thereof will extend away from each other in opposite directions forming what may be termed a V-shaped entrance for each terminal at its inner end. The folds of the strips other than the free terminal portions thereof are arranged in abutting relation. Each contact terminal is mounted on a binding post at a point nearer the outer end of the terminal than the inner end thereof. The washers 28 provide supports for the terminals 31, 32. The circuit conductor 7 is attached to the binding post 26 and the circuit conductor 9 is attached to the binding post 27.

Mounted on the upper face of the plate 19 and positioned between the flanges 21, 22 and the cover member 20, is a conductor member referred to generally by the reference character 33 and best shown in Figure 7. The conductor member 33 is formed from a plate of conducting material, indicated at 34 and slotted lengthwise and with the material freed by the slit upturned to provide a resilient contact finger 35. The plate 34 has its rear part extended upwardly at an inclination, indicated at 36. The finger 35 overhangs the slot 37 formed by the material freed from the slit when upturned to provide the finger 35. The finger 35 extends from a point between the transverse median and rear end of the plate 34 to a point between the transverse median

and forward end of the plate. The plate 34 is secured to the plate 19 by the head 38, of a binding post 39 which extends up through the plate 19. The post 39 extends through the slot 37 and the head 38 of said post seats upon the upper face of the forward portion of the plate 34 to secure the latter in position.

Coacting with the terminal contacts 30 and 32 for the purpose of selectively closing the circuits of the signal 4, is a circuit opening and closing element consisting of an arm 40 formed of insulation material and which has secured to its lower face, a circuit closing member 41 which projects from the forward end of the arm 40. Holdfast devices 43, 43' are employed for securing the circuit closing member 41 to the arm 40. The holdfast device 43 is in permanent electrical contact with the resilient contact finger 35. The circuit opening and closing element is shifted to electrically contact with the contact terminal 31 or the contact terminal 32 by a shifting rod 46, which carries a polygonal shaped nut 45, mounted in a correspondingly shaped opening 44 formed in the arm 40 at the rear end thereof. The rod 46 is provided at its upper end with a right angularly disposed handle 47. A spacing collar is interposed between the nut 45 and the plate 19 and is mounted on the rod 46. A securing nut, for the nut 45, is carried by the rod 46. The rod 46 extends down through the plate 19 and carries on its lower end a retaining cap 51. The lower end of the rod 46 is peripherally threaded as at 50. That part of the rod 46 which is surrounded by the plate 19 is plane as indicated at 51'. The rod 46 is disposed in parallelism with respect to the column 2 and it is connected with said column by a clamping band 52 formed with a barrel 53 for the passage of the rod 46. The securing means for the clamping band 52 is indicated at 52'. The cover member 20 is connected with the steering column 2 by a strap 54, which is secured intermediate its ends, as at 55 to the column 2. Holdfast devices 56, 57 are provided for connecting the end terminal portions of the strap 54 to the cover member 20. The strap 54, in connection with the clamping band 52 maintains the rod 46 in parallelism with respect to the steering column 2. The handle portion 47 of the rod 46 is arranged in close proximity to the steering wheel 3 and projects laterally therefrom. The handle portion 47 is in convenient reach of the driver of the car.

If the circuit opening and closing element is shifted in a direction so that the member 41 engages a contact terminal 31, the circuit to the signal 4 will be closed for the purpose of indicating "Right" and if the circuit opening and closing element is shifted in a direction so that the member 41 will engage the contact terminal 32 the circuit to the signal 138

will be closed for the purpose of indicating "Left". When the circuit opening and closing element is shifted in either direction for circuit closing purposes, it enters between the opened ends of the contact terminals and as these latter are resilient they will frictionally engage the member 41.

It is thought the many advantages of an electrical switching mechanism in accordance with this invention, can be readily understood, particularly in view of the fact that it is in convenient reach of the driver of the vehicle so that it can be actuated to selectively close anyone of the circuits of an electrically operated direction signal to indicate the direction of travel of a vehicle, and although the preferred embodiment of the invention is as illustrated and described, yet it is to be understood that changes in the details of construction can be had which will fall within the scope of the invention as claimed.

What I claim is:

1. An electrical switching mechanism for the purpose set forth comprising a pair of spaced contact terminals each formed of a resilient element having the ends thereof arranged in spaced relation, an oscillatory arm of insulation material, a circuit closing member carried by and projecting from one end of said arm and selectively engaging with said contact terminals at the opposed ends thereof for closing a circuit, a conductor member provided with an offset resilient contact finger in permanent electrical engagement with said circuit closing member and adapted to be permanently connected to a source of electrical energy, and a shifting rod for said arm connected to the other end thereof.

2. An electrical switching mechanism comprising a plate, a pair of spaced binding

posts extending therethrough, oppositely disposed contact terminals carried by said posts and each having the inner end thereof flaring, a shiftable circuit opening and closing element including a circuit closing member cooperating with the flared ends of said terminals and selectively engaging with said terminals for closing a circuit, another binding post extending through said plate, and a conductor member in permanent electrical contact with the last mentioned binding post and formed with an offset resilient contact finger in permanent electrical engagement with said circuit closing member, and shifting means connected to said element.

3. An electrical switching mechanism comprising a plate, a pair of spaced binding posts extending therethrough, oppositely disposed contact terminals carried by said posts and each having the inner end thereof flaring, a shiftable circuit opening and closing element including a circuit closing member cooperating with the flared ends of said terminals and selectively engaging with said terminals for closing a circuit, another binding post extending through said circuit closing member plate, a conductor member in permanent electrical contact with the last mentioned binding post and formed with an offset resilient contact finger in permanent electrical engagement with said circuit closing member, shifting means connected to said element, and a cover member secured to the upper face of said plate and enclosing said conductor member, contact terminals and element, said shifting means extending upwardly through said cover member and further extending through said plate.

In testimony whereof, I affix my signature hereto.

HAROLD E. STORK.
